HEAT TRANSFER AND PRECIPITATION
MEANS

Howell C. Cooper, Sewickley, Pa.

Application December 22, 1945, Serial No. 637,045

1 Claim. (Cl. 62—122)

1
This invention relates to heat transfer and precipitation means and more particularly to gas-to-gas transfer of sensible heat, accomplished by contact of the gas to be processed, with a condensant liquid of low vapor pressure moving at approximately uniform pressure in a condensant cycle, the cycle providing cooling of the condensant before said contact and separation of the resultant condensate from said condensant after contact.

The invention is applicable, as will appear, to the refrigeration art and especially the cascade type of multistage refrigeration. Further, it is applicable to very large quantities of gas and in transferring large amounts of heat; so that it is especially adapted in the liquefaction of natural gases for storage purposes, both as a precoolant for the natural gas, for removal of condensable constituents therefrom before liquefaction, and for interstage heat transfer in the refrigeration system employed in liquefying the natural gas.

The general objects of the invention therefore are to provide a preliquefaction treatment of a gas such as natural gas, involving both precooling of the gas and removal of constituents such as water and carbon dioxide therefrom, in the most effective and economical manner possible; and to such end to provide a heat transfer and precipitation cycle applicable not only to the natural gas to be liquefied, but useful also in the refrigeration system involved in the liquefaction. As will appear, effectively the only net heat loss—if it can be considered a loss—is the refrigeration necessary to solidify the carbon dioxide and liquefy the water to be removed.

Another object of the invention is the selection of a suitable condensant for the purpose intended.

Further objects and advantages will be apparent from the following description taken in connection with the accompanying drawings in which

Fig. 1 is a conventionalized flow diagram of refrigerant treating portions of a natural gas liquefaction system of a capacity in the order of sixty million cubic feet per day,

Fig. 2 is a similar diagrammatic showing of other portions, particularly carbon dioxide and water removing portions, of the same system; the line A—B, Figs. 1 and 2, indicating the location of interconnection of the two separately illustrated portions, to form the complete system.

Fig. 3 is a similar showing of a modification of the portion of the system illustrated in Fig. 2; it being understood that the flow diagrams here appearing are only for illustration of the invention,

2
the invention being equally applicable in other systems, as will be apparent to one familiar with the art.

In the following description, recited temperatures are in degrees Fahrenheit and pressures in pounds per square inch absolute, but it must be appreciated that such figures are recited by way of example only and may be only approximately accurate, it being understood that in the practice of the art some latitude is usually available to the designer, as in the selection of both type and size of equipment units, and in their arrangement.

With reference now to the drawings and first to Fig. 2 thereof, the natural gas to be liquefied, consisting largely of methane, enters the system at 1 and moves successively upwardly through the contact coolers 2 and 3 and downwardly through the condenser 4, from the bottom of which it emerges as a liquid through the pipe 5; the entering pressure being 200 and temperature 70, and the emerging methane product being at a pressure of 20 and a temperature of —240.

For the purpose of substantially cooling the gas ahead of the condenser 4 and at the same time removing condensable constituents therefrom, such as water and carbon dioxide, a condensant is employed in a closed cycle of slight change in pressure, associated with the above described part of the system.

Requisites of the condensant are that it must stay liquid at temperatures low enough to condense the constituents to be eliminated and have sufficiently low vapor pressure that substantially all of it will be retained in its own circuit, the circuit involving intimate contact with the gas being processed. Also, it must be capable of entraining the condensates and yet permit easy separation of the latter therefrom. I have found that pentane, which does not solidify below —200 and the vapor pressure of which does not exceed 14.7 at 90°, nicely serves as condensant for so processing natural gas, but doubtless others, or mingled liquids such as pentane, hexane, heptane and so on might be satisfactory for the purpose.

The condensant circuit includes a heat exchanger 10 wherein it is cooled and from which it flows at a pressure of 205, temperature of —170, sequentially through the contact cooler 3, the centrifuge 11, pump 12, contact cooler 2, centrifuge 13, pump 14, and back to the top of heat exchanger 10 at a pressure of 218, temperature of 60.

In the contact cooler 2, the natural gas moves upwardly and the condensant liquid downwardly, the two being in intimate contact with each other as by spraying or otherwise breaking up the con-

densant into particles falling through the gas as indicated in the drawing, or by spreading of the condensate over baffle plates exposed to the gas, or both, as will be well understood by one familiar with the art. At any rate, the result is that the gas is so lowered in temperature as to condense water therefrom. This water passes downwardly from the contact cooler 2 with the condensate liquid, and is separated from the latter in the centrifuge 13 from which it is removed by way of the pipe 15. The condensate flows from the centrifuge 13 to the pump 14 by which it is delivered back to the heat exchanger 10. The cooled dehydrated gas passes from the top of the cooler 2 and enters the bottom of the contact cooler 3.

In the contact cooler 3 the gas is further cooled, sufficiently to condense carbon dioxide therefrom, employing the condensate from the heat exchanger 10. The condensate liquid enters near the top and leaves at the bottom with entrained carbon dioxide in the form of solid particles, separation takes place in the centrifuge 11 and the condensate is delivered by the pump 12 to the contact cooler 2, the separated carbon dioxide leaving the centrifuge entrained in water, as by the pipe 16. Generally the condensate may remove only sensible heat from the gas within the cooler 3, and a coil 17 may be arranged within the cooler to remove latent heat; the coil being served by a refrigerant as will appear. The gas leaving the contact cooler 3 may be serviced before entering the condenser 4 by a centrifuge 18, and pump 19 in the auxiliary circuit indicated, by which any condensate entrained therein is removed.

For service of the main product condenser 4, as well as the coil 17, a refrigerant such as methane is provided in a cycle involving gas and liquid phases, in a circuit including the condenser 20, Fig. 1, wherein the methane refrigerant is liquefied, and the line *a*, Figs. 1 and 2, leading from the condenser 20 to the condenser 4; this refrigerant returning to its gas phase within the condenser 4, to liquefy the product natural gas, and also in the coil 17 to condense out the carbon dioxide.

This methane refrigerant circuit leads from the condenser 4 through the heat exchanger 10 to the return line *b* Figs. 1 and 2, and the methane leaves the heat exchanger 10 at a pressure of 17 and temperature of 100. By means of the staged compressors 21, 21^a and 21^b and associated interstage contact coolers 22^a, 22^b and 22^c the pressure is raised to 600 at which the methane enters the contact cooler 23. The contact coolers 22^a, 22^b and 22^c are served by cooling water at a temperature of 62, entering by way of the line 24 and leaving by way of the line 25 at a temperature of 85. Water entrained in these interstage coolers is removed by a separator 26. At the same pressure the compressed gas is precooled to a temperature of -126 and water vapor removed therefrom in the contact cooler 23 by service of a liquid condensant such as propane, in a condensant circuit including a cooling heat exchanger 27 which it leaves at a pressure of 605 and a temperature of -130, ahead of the contact cooler 23, and a centrifuge 28 and pump 29 after the contact cooler 23, by which pump 29 the condensate is returned to the heat exchanger 27 at a pressure of 618 and temperature of 90. Action within the contact cooler 23 is generally as described in connection with the contact cooler

2. Water is condensed out of the upwardly flow-

75

ing gas and subsequently removed from the condensant, and the gas leaves the contact cooler at the top at a temperature of -126 and still at a pressure of 600, and enters the heat exchanger 30 for further precooling ahead of the condenser 20.

From the condenser 20 the methane refrigerant passes downwardly through the expansion valve indicated, to the flash tank 31 where it has a pressure of 62 at -200 temperature.

A refrigerant gas bypass 32 leads upwardly from the flash tank 31 through the condenser 20 and into the second stage compressor 21^a at a pressure of 62 and temperature of -140, as indicated.

From the flash tank 31 the liquid methane refrigerant is drawn through the line *a* at a pressure of 62 and temperature of -200, past expansion valves 33 and 34 at a pressure of 20 and temperature of -252, which control respectively, refrigerant service of the natural gas within product condenser 4 and condensing coil 17 within the contact cooler 3.

The heat exchangers 30 and 27, are served by a second refrigerant such as ethylene, in a cycle involving its gas and liquid phases in a circuit generally similar to the methane circuit just described. Principal parts of this circuit are the compressors 40 and 40^a and associated water-served contact coolers 41, 41^a, the contact cooler 42, wherein preliquefaction cooling takes place and water picked up in the coolers 41 and 42^a is condensed out, the liquefying condenser 43, and flash tank 44 with associated expansion valve 44^a. The ethylene refrigerant, in liquid phase at a pressure of 82, and a -90 temperature, leaves the valve 30^a and enters the heat exchanger 30 at a pressure of 20, temperature of -145, and leaves the heat exchanger 27 at a pressure of 17, temperature of 80, enters the contact cooler 42 at 355 pressure, 100 temperature, leaves the contact cooler at a -8° without substantial pressure change, and leaves the condenser 43 in liquid phase.

The contact cooler 42 is served by a condensant liquid such as pentane cooled in the heat exchanger 45 to a temperature of -12 at a pressure of 360 in a circuit including the centrifuge 46 and pump 47 by which the ethylene refrigerant is precooled ahead of the condenser 43 and its water removed, the condensate reentering the heat exchanger 45 at a pressure of 373 and a temperature of 90.

Since the general manner of operation of the ethylene in its circuit is similar to that of the methane in its described circuit, it is thought that further description of the ethylene circuit is unnecessary, to one familiar with the art.

The heat exchangers 43 and 45 are served by a third refrigerant such as propane. The principal elements of the propane circuit are compressors 50, 50^a, water served interstage contact cooler 51, condenser 52, centrifuge 53, expansion valve 54, flash tank 55 and expansion valve 56. The functioning of this propane circuit will be quite apparent to one familiar with the art, particularly in view of the above description of the methane circuit.

With reference now to the modification of Fig. 3, a slightly different pre-liquefaction treatment is provided for the product natural gas. What appears in Fig. 3 is in substitution of what appears in Fig. 2, effectively to the left of line A-B, Fig. 1, similar parts in the figures bearing similar reference characters.

In the arrangement of Fig. 3 separate condens-

sant liquids are employed, in separate circuits, for removing the water and carbon dioxide respectively; illustrative liquids for the purpose being pentane and propane.

The pentane serves the contact cooler 2 to pre-cool the gas and remove water therefrom generally as described in connection with Fig. 2, being itself cooled in the heat exchanger 10.

The propane serves the contact cooler 3 for further cooling of the product gas, and condensation and removal of the carbon dioxide also generally as before, being itself cooled, however, by its own heat exchanger 10a. The heat exchangers 4, and 10a and 10 are arranged in series relation in the methane refrigerant circuit ahead of its first compressor 21.

The advantage of this modified arrangement is that, since propane can be cooled much lower than can pentane, employment of propane for condensation of the carbon dioxide in the contact cooler 3, permits removal of the latent heat of the carbon dioxide without necessitating the coil 17 of Fig. 1 for that purpose.

I claim:

In a natural gas liquefaction system including 25 a product condenser served by a recirculating re-

frigerant: means effective on said gas ahead of said condenser for precipitation of condensable ingredients from the methane in the gas and including means for circulating a condensant liquid of low vapor pressure in a circuit providing successive cooling of said condensant by said refrigerant after said refrigerant leaves said product condenser, contact between said gas and said condensant, and removal of the resultant condensate from said condensant.
